FUSE FOR BOMBS

Sargent P. Huff, Chevy Chase, Md., and William Summerbell, Watervliet, N. Y.

Application March 24, 1937, Serial No. 132,766

4 Claims. (Cl. 102—36)

(Granted under the act of March 3, 1883, as amended April 30, 1928; 370 O. G. 757)

The invention described herein may be manufactured and used by or for the Government for governmental purposes, without the payment to us of any royalty thereon.

5 This invention relates to a fuse for bombs.

In a fuse for bombs it is customary to employ a vane unit which rotates during flight of the bomb and controls arming of the firing mechanism. In order to insure the safety of the fuse

10 while the bomb is carried in the launching rack of an aircraft the vane unit is held against rotation by an arming wire which is withdrawn when the bomb is released.

The purpose of this invention is to provide a 15 fuse construction in which the vane unit may be readily and conveniently applied to the fuse and a driving connection established by a movement axially of the fuse so that the arming wire may be inserted through the vane unit before the assembly operation.

20 With the foregoing and other objects in view, the invention resides in the novel arrangement and combination of parts and in the details of construction hereinafter described and claimed, it being understood that changes in the precise embodiment of the invention herein disclosed may be made within the scope of what is claimed without departing from the spirit of the invention.

25 A practical embodiment of the invention is illustrated in the accompanying drawing, wherein:

Fig. 1 is a longitudinal sectional view with parts in elevation of the improved fuse.

Fig. 2 is a similar view showing the pre-assembled vane unit about to be placed on the fuse.

30 The invention is illustrated as applied to a fuse of the type shown in Patent No. 2,054,111 of September 15, 1936, in which a fuse casing 5 that is adapted to be secured to a bomb rotatably 35 mounts a spindle 6 whose inner end is arranged to be unthreaded from a member 7 during flight. A sleeve 8 fixed to the spindle and a nut 9 fixed on the sleeve cooperate to establish an inner race for ball bearings 10 while a rotor 11 has a groove 12 which establishes the outer race for the bearings. A gear 13 is fixed on the sleeve while a gear 14, having one tooth less than the gear 13 is loosely mounted thereon and has a pin 14a which holds it against rotation but permits axial 40 displacement. Both gears are in mesh with a planet pinion 15 carried by the rotor. The purpose of the reduced motion gearing is to enable the rapidly rotating rotor to drive the spindle at a slow rate.

50 The rotor is provided with a pair of oppositely

disposed apertured ears 16—16 which are held in place by driving pins 17 and overlie an apertured flange 18 on the casing 5. A cotter pin 19 inserted through one set of apertures normally holds the rotor against movement during transportation and storage and is removed after the arming wire 20 is inserted in the opposite set of apertures. This arming wire is part of the launching apparatus of an aircraft and is withdrawn when the bomb is released.

5 The vane unit comprises a hollow nut 21, and an encircling collar 22 whose lower or inner end is formed with an internal flange 23, an external flange 24 and a pair of slots 25—25. Vanes 26 are formed integrally with a ring 27 which is 10 supported on the external flange 24 and secured by rivets 28 positioned in line with the slots 25. A pin 29 on the collar extends into an annular groove 30 in the outer surface of the nut 21 and maintains the assembly of these units while permitting relative longitudinal and rotational 15 movement. One or more of the vanes are provided with an aperture 31 for receiving the arming wire 20.

The bomb including the fuse without the vane 20 unit is mounted in place on the aircraft and the arming wire 20 applied to hold the rotor 11, after which the cotter pin 19 is removed. The vane unit is now assembled to the fuse by moving it axially thereof and prior to or during the 25 operation the arming wire is passed through the aperture 31 in the vane. The collar 22 is advanced until it engages the rotor 11, the slots 25 receiving the driving pins 17 which now hold the collar against rotational displacement. The 30 nut 21 is now threaded onto the rotor until it is brought up against the internal flange 23 of the collar. The nut now serves to hold the collar in driving engagement with the pins 17 on the 35 rotor.

40 When the bomb is launched, the air pressure acts on the vanes 26 to spin the collar 22 and the collar acts through the pins 17 to drive the rotor. The movement of the rotor controls the arming of the fuse through the specific gear 45 mechanism shown or in any other well known manner.

We claim:

1. In a fuse, the combination with a support, a rotor mounted on the support, pins on the 50 rotor, and an arming wire engaging the support and rotor, of a preassembled vane unit including a collar having slots for receiving the pins on the rotor, vanes on the collar at least one of which has an aperture for receiving the arming 55

wire, a nut within the collar and threaded on the rotor to engage and maintain the collar in driving connection with the pins on the rotor, said nut having an annular groove on its outer side, 5 and a pin on the collar disposed in the groove.

2. In a fuse, the combination with a support, a rotor mounted on the support, pins on the rotor and an arming wire engaging the support and rotor, of a preassembled vane unit comprising 10 a collar and a nut within the collar, means for connecting the collar and nut for relative rotational and limited sliding movement, said collar having slots for receiving the pins on the rotor, vanes on the collar at least one of which 15 is engageable by the arming wire, and said nut when threaded on the rotor engaging and maintaining the collar in driving engagement with the rotor.

3. In a fuse, the combination with a support, 20 a rotor mounted on the support and an arming

wire engaging the support and rotor, of a pre-assembled vane unit comprising a collar and a nut arranged for relative rotational and limited sliding movement, vanes on the collar at least one of which is engageable by the arming wire, 5 and said nut when threaded on the rotor engaging and maintaining the collar in driving engagement with the rotor.

4. In a fuse, a support, a rotor mounted on the support, an arming wire passing through the support and rotor, a member movable axially of the fuse into driving engagement with the rotor and having means whereby it is engaged by the arming wire, and a nut within said member and 10 threaded on the rotor, said nut engaging and maintaining said member in driving engagement with the rotor. 15

SARGENT P. HUFF.

WILLIAM SUMMERBELL. 20
